UNITED STATES PATENT OFFICE.

THEODORE J. H. EGGENSTEIN, OF CHICAGO, ILLINOIS.

FRICITION SHOCK-ABSORBING DEVICE.

1,160,153.

Specification of Letters Patent. Patented Nov. 16, 1915.

Application filed November 13, 1913. Serial No. 800,738.

To all whom it may concern

Be it known that I, THEODORE J. H. EGGENSTEIN, a subject of the Queen of the Netherlands, residing at Chicago, county of Cook, State of Illinois, have invented a certain new and useful Improvement in Friction Shock-Absorbing Devices, and declare the following to be a full, clear, and exact description of the same, such as will enable others skilled in the art to which it pertains to make and use the same, reference being had to the accompanying drawings, which form a part of this specification.

My invention has for its object to produce a simple compact and powerful device for absorbing shocks without permitting an objectionable recoil.

My invention is peculiarly adapted for use in the draft gears of railway cars and in the drawing accompanying this specification I have illustrated the invention as embodied in a railway draft rigging.

In the accompanying drawing: Figure 1 is a top plan view of one end of the draft sills of a railway car having associated therewith a draft rigging arranged in accordance with a preferred form of my invention; and Fig. 2 is a section taken approximately on line 2—2 of Fig. 1.

Referring to the drawing, 1 and 2 represent the draft sills of a railway car, while 3 and 4 are separated stop plates lying between and connecting the draft sills together.

5 is a draw bar having instead of the usual yoke an elongated spiral, 6, rigidly connected to the rear end thereof and projecting through and guided by the stop plates 3 and 4. If desired, the stop plates 40 may be provided with suitable bushings, 7, serving to form bearings for the spiral and adapted to protect the stop plates from wear due to the inward and outward movement of the spiral. Between the stop plates and 45 of a length equal substantially to the distance between the stop plates is a drum, 8, having an eccentric opening extending longitudinally therethrough for receiving the spiral; the said opening being parallel with the axis of the drum and being internally shaped in the form of a spiral complementary to the spiral 6. Beneath the drum is a transverse plate, 9, secured at its ends to the two draft sills.

10 is a strap or band overlying the drum and having its ends attached to bolts, 11

and 12, which pass down beside the plate 9 or through a transverse slot, 13, in the plate. On the bolts are strong springs, 14, engaging at their upper ends with the under 60 side of the plate 9 and at their lower ends with nuts, 15, on the bolts.

It will be seen that the strap or band 10 is held against the drum under spring tension, the tension depending on the strength 65 of the springs and the distance to which the nuts 15 are screwed upon the bolts.

The parts are so disposed that when the coupler head is lying in its intermediate position, that is in the position ordinarily occupied by coupler heads when they are under neither a pulling nor a buffing strain, the drum is symmetrically disposed on opposite sides of a vertical plane passing through the axis of the spiral and also 75 through the axis of the drum; that is, the large side of the eccentric being at the bottom.

The operation is as follows: When a buffing strain comes upon the coupler, the spiral 80 carried thereby is forced back, first carrying the drum into contact with the rear stop plate 4 and then turning the drum in one direction or the other, for example, the clockwise direction. As the drum turns it 85 slides upon the band or strap 10 so as to oppose the rearward movement of the coupler head with a frictional resistance. On account of the eccentricity of the drum the yoke-like strap or band is lifted bodily as 90 the drum turns and thus increases the tension on the springs. As the tension on the springs increases the friction between the drum and the strap or band also increases. Assuming the coupler to be connected to a 95 corresponding coupler or another car and to be subjected to a pulling stress, the tendency of the spiral 6 is to move forward or outward and, in so doing, it first draws the drum into contact with the front stop plate 3 and then begins to rotate the drum in the opposite direction from that which takes place under buffing stresses, again placing the springs under an increased tension. It will thus be seen that when the 100 draw bar is placed under either a buffing or a pulling stress, movement of the draw bar will be resisted by combined spring and frictional resistance, friction occurring between the surfaces of the spirals on the draw 105 bar and in the drum, between one end of the drum and one of the stop plates, and be-

2
between the drum and the band or strap engaging the same; the friction increasing as the push or pull increases. Furthermore, the initial resistance, that is the resistance to slight movements of the draw bar in either direction may be made comparatively small so that the rigging will not be so stiff as to make it unable effectively to absorb slight shocks. A very important advantage is that there is no recoil after a buffing or a pulling shock.

It will thus be seen that with a few simple parts I am able to produce an efficient shock absorber which will effectively absorb shocks imposed upon it in either of two directions without having any objectionable recoil. It will also be seen that while my invention is particularly useful in connection with draft gears for railway cars it is not limited to this single field but may be used to advantage wherever it is desired to have an efficient shock absorbing cushion.

I claim:

1. In combination, a drum, a spiral extending into a complementary opening in said drum arranged parallel with and at one side of the axis of the drum, a support fixed relative to the spiral in the transverse direction, a band passing over said drum, and a spring between said band and said support.

2. In combination, a drum, a spiral extending into a complementary opening in said drum arranged parallel with and at one side of the axis of the drum, a friction member, and means for yieldably pressing said friction member against the periphery of the drum.

3. In combination, a frame containing two separated stop plates, a drum lying between and adapted to engage at its ends with said stop plates, a spiral extending through said stop plates and through said drum and engaging with a complementary opening in the drum arranged at one side and parallel with the axis of the drum, a friction band partially surrounding the drum, and yieldable means between the ends of said band and the frame for pressing the band against the drum.

4. In combination, a frame containing two separated stop plates, a drum lying between and adapted to engage at its ends with said stop plates, a spiral extending through said stop plates and through said drum and engaging with a complementary opening in the drum arranged at one side and parallel with the axis of the drum, a friction band partially surrounding the drum, screw threaded rods connected to the ends of the band, adjustable nuts on said rods, and compression springs surrounding the rods and arranged between said nuts and said frame.

5. In combination, two members connected together by a spiral arranged parallel with and at one side of the axis of one of said members, and a yieldingly-pressed friction device engaging the periphery of the latter member.

In testimony whereof, I sign this specification in the presence of two witnesses.

THEODORE J. H. EGGENSTEIN.
